UNITED STATES PATENT OFFICE.

JOHN W. WEST, OF EAST BRAINTREE, MASSACHUSETTS.

CONTROLLING DEVICE FOR WINDING-MACHINES.

1,143,003.

Specification of Letters Patent. Patented June 15, 1915.

Application filed June 29, 1912. Serial No. 706,623.

To all whom it may concern:

Be it known that I, JOHN W. WEST, of East Braintree, in the county of Norfolk and State of Massachusetts, have invented 5 certain new and useful Improvements in Controlling Devices for Winding-Machines, of which the following is a specification.

This invention relates to a device for controlling winding machines, whereby uniform lengths of thread may be wound upon 10 holders, such as spools or tubes. In my Patent No. 1,030,147 dated June 18, 1912, I have shown a device of this character in which the winding operation is stopped by a 15 mechanically controlled mechanism.

One feature of the present invention contemplates the provision of electro-responsive means for controlling the winding operation when a predetermined weight of thread has 20 been wound upon the holder.

A further feature contemplates the provision of means for automatically severing the thread when the predetermined amount of thread is wound upon the holder. The 25 winding operation may be stopped without severing the thread, or the thread may be severed without stopping the machine when a full length has been wound, or the device may be arranged to sever the thread and 30 stop the machine simultaneously.

The invention will be clearly understood from an inspection of the accompanying drawing, in which—

Figure 1 is a fragmentary front elevation showing one embodiment of the invention applied to a so-called "Universal" winding machine, Fig. 2 is a side elevation of the same, Fig. 3 is a perspective detail view of the contact arm and knife, Fig. 4 35 is a side elevation, partly diagrammatic, of a modified form of the invention, and Fig. 5 is a fragmentary side elevation showing a thread guide.

The present embodiment of the invention 40 is shown applied to the well known "Universal" winding machine, which is illustrated and described in the patent granted to S. W. Wardwell, No. 801,941 dated October 17, 1905, but it should be understood 45 that the invention is readily applicable to other styles of winding machines.

As illustrated in Figs. 1 to 3, inclusive, the winding machine comprises a frame 10, having a winding spindle 12, driven by a 45 pulley 14, the latter being shown in Fig. 4 only. A thread holder 16, which may be a

tube or a spool, is held on the winding spindle by a nut 17, and upon this holder the mass of thread 18 is wound from the supply. The supply of thread may be supported in various ways, for example, in this form of the device it is intended to be supported in the manner shown in my said patent. The thread passes from the supply to a tension device 20, thence under a finger 22 on a wire lever 24, the latter being fulcrumed at 25 on a sector 26 of a stop-motion device carried by a swinging traverse frame 28. The sector is fulcrumed at 27 on the main frame 10. The lever 24 is 50 formed with a leg 30 composed of wire, the inner end of which hangs adjacent to the corrugated rim of a wheel or disk 32 carried by a cam shaft 34 and rotating in the direction of the arrow. From the finger 22 55 the thread passes to a reciprocating guide 23. Whenever the thread breaks, the finger 22 is unsupported and the lever tilts so that the loop or leg 30 engages the rim of the wheel 32, whereupon the stop-motion is actuated as explained in the patent to Wardwell above mentioned.

My device is adapted to be applied bodily to the above described winding machine without changing any of its instrumentalities above set forth. In order to accurately control the stopping of the winding operation when a predetermined amount of thread is wound on the holder, I provide means for holding a supply of thread which is arranged to be balanced. The balancing device may be such as is shown in my said patent, in which a plurality of like, net thread weights and adjustable weights are arranged to balance the supply. A rod 40, 90 similar to the rod 48 of my said patent, is adapted to support the thread from which a holder is filled. This rod depends from the balancing device, as shown in my said patent, and is provided with an arm 42 insulated therefrom by a bushing 43, and having a contact 44 at its free end. A conductor 46 connects the contact 44 with one pole of a battery 47, and the other pole of the battery is connected by a conductor 48 95 to one terminal of an electromagnet 50. The other terminal of the electromagnet is connected by a conductor 52 to a stationary contact 53, mounted on, but insulated from, the frame 10. An armature 54 for the electromagnet is mounted on the sector 26, said magnet being supported by a bracket 55

affixed to the frame 10. In this form of the device the winding operation is commenced by removing one of the net thread weights, as explained in my said patent, whereupon the rod 40 is lowered and the contacts 44 and 53 are separated. If the thread breaks, the stop-motion is actuated as explained in the above mentioned patent to Wardwell. When the required amount of thread is wound upon the holder 16, the balance is restored and the rod 40 rises to bring the contacts 44 and 53 into engagement. The circuit through the electromagnet 50 is thus closed and the latter is thereby energized. The electromagnet attracts its armature 54 and thus swings the sector 26 about its fulcrum 27 to actuate the stop-motion, whereupon the winding operation is stopped.

In some instances it may be desirable to automatically sever the thread when the predetermined amount has been wound upon the holder. To accomplish this a bar 56 is affixed to the rod 40 in proximity to the finger 22 and provided with a dovetail slot 57 having its inclined edges 58 sharpened to form knives. During the winding operation the thread passes from the tension device in proximity to the upper edge of the bar 56, then under the finger 22, and through the reciprocatory guide 23. When the balance is restored, by having the desired length of thread wound upon the holder 16, the bar 56 is raised into contact with the thread. The vibrating thread is thus caught in the notch 57 and drawn against one of the knives 58 and severed, thus preventing the thread from being wound upon the holder.

In Fig. 4 I have shown a modified form in which the balancing device 60 is mounted upon the floor, the supply of thread 61 being balanced by the net thread weights 62 and the adjustable weights 63 and 64. A stationary contact 66 is mounted on, but insulated from, the base of the scales 60, and the coöperating movable contact 67 is mounted on, but insulated from, the beam of the scales. The contact 66 is connected by a conductor 68 to one terminal of an electromagnet 50, the other terminal of said magnet being connected by a conductor 70 to one terminal of a battery 72. The other terminal of the battery 72 is connected by a conductor 74 with the movable contact 67. The operation of this form of the device is obvious from the explanation given above. It obviates the necessity of the rod 40 and connected parts at the front of the machine. In Fig. 5 I have shown a modified form of thread guiding means adapted for use when the balancing device is mounted upon the top of the winding machine. It comprises a rod 80 affixed to a scale pan 81 and bent at right angles to form a horizontal arm 82, the latter being provided with two thread-guiding eyes or loops 83, 84. By using this

form of guiding means, all of the supply may be mounted at one point and the thread drawn therefrom during the winding operation, instead of supporting one lot from the rod 40 and the remainder upon the scale pan, as shown in my said patent. If desired this form of thread guiding means may be employed with the scales in the position shown in Fig. 4.

While I have illustrated and described a preferred embodiment of the invention, I am aware that many modifications can be made therein by any person skilled in the art without departing from the scope of the invention as expressed in the claims. Therefore I do not wish to be limited to all the details of construction shown and described, but

What I claim is:

1. A winding machine having means for winding thread upon a holder and a stop motion device for controlling the winding operation, said stop motion device including an electric actuator therefor and a movable element controlled by the weight of the thread for governing the circuit of said actuator.

2. A winding machine having means for winding thread upon a holder, a stop motion device for controlling the winding operation, an electric actuator for said stop motion device, a circuit therefor and means controlled by the weight of the thread adapted under a predetermined weight to maintain said circuit in open condition and to close the circuit upon an adjustment gained through the loss of said predetermined weight.

3. A winding machine having means for winding thread upon a holder, a stop motion device for controlling the winding operation, electro-magnetic means including a circuit for actuating the stop motion device upon energization of said electro-magnet, the circuit for the electro-magnet including a movable and fixed contact and an element controlled by the weight of the thread operating the movable contact whereby under a predetermined excess weight the contacts are maintained in open relation and upon the loss of said weight the contacts are brought into engagement to close the electro-magnetic circuit.

4. A winding machine having means for winding thread upon a holder, a stop motion device to control the winding means, a thread cutter arranged for coöperation with the thread, and electro-magnetic means controlled by the weight of the thread for simultaneously operating the stop motion device and thread cutting device.

5. In combination with a thread winding means, a stop motion device to stop said winding means, a thread-cutting device movable to cut the thread as it leads to said

winding means, and a device controlled by thread-weight and movable to operate said stop motion device and said thread cutting device when a predetermined weight of 5 thread has been wound on said winding means, substantially as described.

6. In combination with thread winding means, a stop motion device, electrically-operated devices for actuating said stop motion device to stop said winding means, electrical contact devices relatively movable to control said electrically-operated devices, a thread-cutting device, movable to cut the thread as it leads to said winding means, and a device controlled by thread-weight and movable to operate said contact devices and said thread cutting device when a predetermined weight of thread has been wound on said winding means, substantially as described.

7. The combination with a winding machine having means for winding thread upon a holder, of a stop-motion device for stopping the machine, a balancing device 25 provided with a support for a supply of thread, a normally open electric circuit including an electromagnet, and means operated by said balancing device adapted to close said circuit when a predetermined 30 weight of thread has been wound upon the holder, said electromagnet being arranged to actuate said stop motion device when said circuit is closed.

8. The combination with a winding machine having means for winding thread upon a holder, of a stop-motion device for stopping the winding operation, said device having a pivotally mounted member, an electro-responsive device adapted to swing 40 said member to actuate said stop-motion device, and a device governed by thread-weight and arranged to control said electro-

responsive device when a predetermined weight of thread has been wound upon the holder.

9. In combination with thread winding means, a stop motion device, electrically operated devices for actuating said stop motion device to stop said winding means, electrical contact devices relatively movable 50 to control said electrically operated devices, a thread cutting device, movable to cut the thread as it leads to said winding means, and a device controlled by thread-weight and vertically movable to operate said contact devices and said thread-cutting device when a predetermined weight of thread has been wound on said winding means, substantially as described.

10. The combination with thread winding means, an actuating thread-weight governed device to move from an initial position when a predetermined weight of thread has been wound on said winding means, a stop motion device, electrically operated devices for actuating said stop motion devices to stop said winding means, controlling means for said electrically operated devices, comprising a pair of contact devices, one disposed to be moved by said actuating device on movement thereof from its initial position, to cause operation of said stop motion device, and a thread cutting device, movable by said actuating device, during its movement from initial position, to cut the thread leading to said winding means, substantially as described.

In testimony whereof I have affixed my signature, in presence of two witnesses.
